Primary Examiner — Cynthia Ramirez*Assistant Examiner* — Laura H Yu(74) Attorney, Agent, or Firm — Shook, Hardy and Bacon L.L.P.(57) CLAIM

The ornamental design for a shoe, as shown and described.

DESCRIPTION

FIG. 1 is a side view of a shoe showing my design;

FIG. 2 is a front perspective view thereof;

FIG. 3 is a rear perspective view thereof; and,

FIG. 4 is a rear view thereof.

The even-length broken lines are directed to environment, represent unclaimed subject matter, and form no part of the claimed design.
